UNITED STATES PATENT OFFICE.

EDWARD A. JARVIS, OF PORT RICHMOND, NEW YORK.

MEANS FOR SAFELY CONDUCTING ELECTRIC CURRENTS.

SPECIFICATION forming part of Letters Patent No. 760,740, dated May 24, 1904.

Application filed December 16, 1903. Serial No. 185,433. (No model.)

To all whom it may concern:

Be it known that I, EDWARD A. JARVIS, a citizen of the United States, and a resident of Port Richmond, in the county of Richmond and State of New York, have invented certain new and useful Improvements in Means for Safely Conducting Electric Currents, of which the following is a specification.

The object of this invention is to provide a means whereby high-potential electric currents can be conveyed along a public highway with safety to life, also to cheapen the construction of electric railroads by doing away with the underground conduit, this means being an insulated conductor with special means for drawing the current from the conductor as a car or train proceeds, it being equally well adapted for elevated structures.

In the drawings forming a part of this specification, Figure 1 is a cross-section taken on a line *a a* of Fig. 2 and illustrates an electrical conductor incased in a conduit of non-conducting material; and Fig. 2 is a longitudinal section of a portion of a rail, showing the arrangement of the armatures, &c. Fig. 3 illustrates the rail in combination with a contact-shoe of the common type, a magnet and motor circuit being included, also showing some of the armatures in contact. Fig. 4 is an end view of Fig. 3. Fig. 5 illustrates the invention as applied to a metal rail, and Fig. 6 is a perspective view of the general appearance of a finished rail. Fig. 7 is a modification and illustrates how the device may be applied to a contact-rail already in place. Fig. 8 illustrates a filler for the modification shown in Fig. 7.

Referring to Fig. 1 and considering it as but one of many ways in which the invention can be constructed, 2 represents a rail or string-piece of non-conducting material, such as wood, formed of one or more pieces. Longitudinally and preferably in the center of the rail 2 is a slot or conduit 3, which carries an electrical conductor 4, which may be of any desired shape or conducting material. Transversely of the rail 2 are cut a desired number of slots 5, which slots intersect the central slot 3 and extend below the said slot, as shown. Within

matures 6, of suitable material, having flat bottoms to prevent tilting and which rest upon the bottom of the slots 5, the said armatures straddling the conductor 4, but out of contact with the said conductor, and for the purpose of keeping the armatures out of contact from transverse movement a block of non-conducting material 7 may be inserted in the top of the slots 5, the block to be slightly less in width than the distance between the legs of 60 the armatures 6.

It will be noticed that the leg 8 of the armatures is somewhat longer than the leg 9, the purpose of this being to insure good contact, for the following reason: When the armature is pulled up by the magnet, the longer leg will contact first. The shorter leg will continue to move until arrested by the contact between the armature and primary conductor. This pull will have the effect of giving a good 70 contact. Upon the top of the rail conductors 10 are fastened, the word "top" being used as descriptive of the view only. These conductors receive the current from the primary conductor 4 through the armatures 6. By referring to Fig. 2 it will be seen that the conductors 10 are insulated from each other at 11, this being for the purpose of preventing the whole system from being charged when contact is made through the armatures, which would occur if 80 the conductor was a continuous strip. By this means only those sections which are within the scope of the contact-shoe are charged, as will appear hereinafter. To still further insulate the conductor 4, strips 12, of non-conducting 85 material, can be applied to the sides of the rail 2, thereby covering the slots 5. The sections 10 may be of any desired length and any desired number of armatures may be employed.

For the purpose of operating the armatures 90 6 a magnetic contacting shoe 13, Fig. 3, is employed, the said shoe being included in a motor-circuit 14, the said motor-circuit having connected thereto an electromagnet 15 of the horseshoe type, although any other type 95 may be used. The core 16 of the magnet is fastened to the shoe, and the bobbins 17 17 encircle the core, as is common. The contact-shoe is preferably a permanent magnet, for reasons to be hereinafter explained.

As is illustrated by Fig. 3, the magnet 15 is in parallel with the motor-circuit, this being for the purpose of keeping the shoe magnetized when the power is shut off from the motor. As connecting in parallel is well understood, further explanation is deemed superfluous. The ground 18 represents the return-circuit.

In Fig. 5 a sectional metal rail 20 is shown 10 as having a conduit or slot 21 therein, the said conduit being insulated at 22, if desired, and containing a conductor 23, supported free from contact by insulators 24, armatures 25 acting, as the armature 6 of Fig. 1, to convey current 15 to the secondary conductor 26, which is in sections, as in Fig. 2. The same general description applies to Figs. 1 and 5.

Fig. 7 illustrates a rail 27, insulated by non-conducting material 28, the said material carrying a secondary contact 29 in sections, the armature 30 being somewhat different from the armatures 6 and 25. Upon the top of the rail a slotted non-conductor 33 may be placed, Fig. 8, in which slots the leg 31 of the armature 30 rests. The leg 31 is shown as tapered, with the base 32 of the taper comparatively close to the sections 29. Normally the armature 30 will be out of contact with the conductors, the length of the leg 31 being suitable for this purpose, as illustrated.

When the armature is pulled up, the base 32 of the leg 31 will contact first, acting as a fulcrum for the leg 31, which by continued movement will tend to throw the leg 32 against the rail 27, thereby getting a firm contact. The action of the device, briefly, is as follows: As the car moves and the contact-shoe 13 proceeds 35 the armatures will be pulled up by magnetic attraction, thereby closing the circuit between the primary conductor and the secondary. Those armatures over which the shoe is only 40 will be attracted. The others will be down. Thus not more than two sections will be alive at a time and those being the ones with which the shoe is contacting, it being understood 45 that the current which is shunted through the magnet 15 supplies the power to obtain this attraction. When the power is shut off for the purpose of a stop, there will be current 50 still in the magnet-circuit, which will hold up those armatures over which it is. Consequently when power is needed again it is available. The purpose of having the contact-shoe a permanent magnet is apparent, as 55 in the event of the shutting off of the power at the power-house there would be no current in the magnet-circuit and it would be impossible to hold up the armatures, but up to the time of the cessation of power some of the 60 armatures would be in contact, and after the current had gone the permanent magnet would exert enough force to hold the armatures, thereby insuring current for the motor when needed.

It will be readily conceded that those sections with which the shoe contacts temporarily become part of the magnet. The size of the armatures will be suitable for conduction and weight sufficient to insure their dropping as the shoe leaves them.

It is apparent from the foregoing that the rail is harmless to life, as it is impossible to get current without a powerful magnet. Therefore it is possible to lay the rail in a street and upon the surface thereof.

For the sake of clearness it may here be stated that the shoe 13, which is a permanent magnet, does not act to the detriment of the electromagnet 15 to the same extent as a non-magnetized shoe would, as in the latter case a dead magnetic short circuit would result. Furthermore, the extent of the short circuit, even in the case of a non-magnetized shoe, would be dependent upon the amount of material lying between the two poles in proportion to the magnetic strength. As an illustration, if an iron wire was placed to connect the two poles the short circuit would hardly be noticed, while an iron bar, if large, would cause a dead short circuit. If the connecting-strip be a permanent magnet, as in this case, the action of the electromagnet would be to increase the strength of the permanent magnet, due to the fact that the shoe was already charged and exerting at all times the same magnetic field that the electromagnet would impart to it, but not of the same strength. That a permanent magnet loses its strength shortly after the cessation of magnetic influence is well known. In other words, it will 100 not retain all of the magnetism imparted to it, and if a more powerful magnet is brought in contact with it its strength is increased during the period of contact. Such is the object of the hereinbefore-described combination.

Having described my invention, what I claim, and desire to cover by Letters Patent, is—

1. The combination of a primary conductor, a secondary conductor insulated therefrom, a motor-circuit, a collecting means contacting the secondary conductor, the said collecting means consisting of a permanent magnet, an electro horseshoe-magnet having both poles supported by the permanent magnet, the electromagnet being connected in parallel with the motor-circuit, together with means acted upon by the magnets whereby current can be conveyed from the primary to the secondary conductor thence to the motor-circuit through the collecting means.

2. The combination of a primary conductor and a secondary conductor insulated therefrom, of means adapted to close the circuit between the two conductors, together with magnetic means acting to operate the circuit-closing means, the said magnetic means consisting of a permanent magnet having attached

thereto both poles of an electro horseshoe-magnet whereby the permanent magnet is strengthened during the period of excitement of the said electromagnet.

5 3. As a source of magnetic energy, the combination of a permanent magnet, and an electro horseshoe-magnet the said permanent magnet supporting both poles of the said horseshoe-magnet, whereby the permanent magnet

is strengthened during the period of excitement of the electromagnet.

Signed at New York, in the county of New York and State of New York, this 15th day of December, A. D. 1903.

EDWARD A. JARVIS.
